STARTING DEVICE FOR NON-SELF-START-
ING PHONOGRAPH MOTORSHerman Cornelis Van Doorn, Eindhoven, Nether-
lands, assignor to Hartford National Bank and
Trust Company, Hartford, Conn., as trusteeApplication July 3, 1946, Serial No. 681,393
In the Netherlands August 4, 1943Section 1, Public Law 690, August 8, 1946
Patent expires August 4, 1963

5 Claims. (Cl. 318—174)

1

Though non-self-starting motors, for instance synchronous motors in phonograph installations, have advantages over the other usual types, since they operate at a constant speed without special precautions and, particularly since their manufacture is much cheaper, they naturally have inherent therein the drawback that they cannot start automatically. For instance, the turntable has to be set in motion initially either directly by hand or by means of a special mechanism when starting operation of the phonograph.

Starting devices for synchronous motors are known. These may comprise a spring which is first stretched and whose energy is then released for driving the mechanism, by means of which the turntable is set in motion and the electric circuit of the motor is completed. The spring is stretched by means of an arm, which is moved by hand and is locked automatically, for instance by means of a pawl, at the end of the stroke. Only after this operation is the phonograph ready for use. The phonograph is started up by pressing a knob, as a result of which the aforesaid arm and the spring connected thereto are released. Owing to the aforesaid release of the spring, the mechanism and finally the motor are set into motion. After that, the groove scanner has to be placed on the record.

The present invention concerns a similar starting device but has for its purpose the simplification of the operations for starting up the motor. According to the invention, this is achieved by carrying out the required operations exclusively by means of the arm of the groove scanner.

The device according to the invention is preferably designed in such a manner that the stretching and release of the said spring takes place by one outward displacement of the groove scanner. In this case the operation of the phonograph takes place similarly to the common automatic talking machines having self-starting motors, in which the scanner is slightly turned outwards to start up the motor. In this respect the use of a synchronous motor outwardly corresponds entirely to that of a self-starting motor.

In order that the invention may be clearly understood and readily carried into effect, it will now be explained more fully with reference to the accompanying drawing, given by way of example and representing one embodiment thereof.

The sole figure represents a starting device according to the invention and according to the last-mentioned executional example. When the arm of the groove scanner 1 is moved outwards and is thus turned on the base 2 in the direction

2

of the arrow A, it drives, by means of the shaft 3 which is rigidly mounted therein, the ratchet wheel 4 which in its turn is rigidly mounted on the shaft 3. The toothed segment 5 is loosely movable about the shaft 3. The pawl 6, however, engages the ratchet wheel 4 and is mounted on the segment 5 at the centre of rotation 7, so that the segment as a whole follows the movement of the ratchet wheel in the direction of the arrow A. In this way the draw spring 18, one end of which is secured to the segment, is stretched. However, the pinion 9 does not yet engage the segment 5, as long as the rubber driving wheel 15 which is rigidly secured to the pinion through the intermediary of the shaft 14, stands free from the turntable. The said engagement only takes place when the pin 10, which is mounted on the segment 5, abuts against the cam 11. As a result thereof a small displacement of the lever 12, in which is journalled the shaft 14 with the pinion 9 and the wheel 15, allows the drawspring 16 to turn the lever 12 over such an angle that the pinion 9 and the teeth of the segment 5 engage each other and at the same time the wheel 15 is pushed against the turntable. Upon this engagement a further small angular displacement of segment 5 results in that the pawl 6 abuts against the pin 17 at 6a. Owing to this the pawl is moved away from the ratchet wheel and remains in this position under the action of the plate spring 8 which permits a permanent active and inactive position of the pawl. The plate spring 8, in effect, is secured with a pin 8a to the segment and has such a length that both in the active and in the inactive position no couple is exerted on the pawl in contradistinction to all intermediate positions.

After the segment 5 has been disengaged from the ratchet wheel 4, the draw spring 18 becomes operative and withdraws the segment in a direction opposite to that of the arrow. This results in that the pinion 9 is made to rotate which in its turn drives the wheel 15 engaging the turntable 19, so that the turntable 19 is made to rotate in the direction of the arrow B. At the end of the stroke the returning segment 5 disengages the pinion 9, through the intermediary of the pin 20 which abuts against the cam 11 and at the same time the contact between the wheel 15 and the turntable 19 is removed. A suitable stop (not represented) provides that the lever 12 cannot be moved back too far by the spring 16. Upon abutment of the pin 20 against the cam 11 a further angular displacement of the segment results in that the fixed pin 21 engages the side 6b of the

pawl 6, so that the pawl is made to engage the ratchet wheel 4 again. At the same time the contact springs 22 and 23 are interconnected through a locking member 24 which is secured on a block of insulating material to the segment 5. This results in that the main voltage is applied to the motor which is now capable of continuing the driving of the mechanically started turntable.

What I claim is:

1. A starting device for a non-self-starting phonograph comprising a non-self-starting electric motor, a turntable operatively connected thereto, a groove scanner arm operatively associated with said turntable, means for setting said non-self-starting electric motor in motion, and other means for initiating operation of said first means, said other means being mechanically linked to and positively actuated by manual movement of said groove scanner arm.

2. A starting device for a non-self-starting phonograph comprising a non-self-starting electric motor, a turntable operatively connected thereto, a groove scanner arm operatively associated with said turntable, first means for setting said non-self-starting electric motor in motion, second means for initiating operation of said first means, said second means being mechanically linked to and positively actuated by manual movement of said groove scanner arm, and switch means for said non-self-starting electric motor which are closed by manual movement of said groove scanner arm.

3. A starting device for a non-self-starting phonograph comprising a non-self-starting electric motor, a turntable operatively connected thereto, a groove scanner arm operatively associated with said turntable, spring means for setting said non-self-starting electric motor in motion, pawl and ratchet means for placing tension on said spring means, said pawl and ratchet means being mechanically linked to and positively actuated by manual movement of said groove scanner arm, abutment means for rendering said pawl and ratchet means inoperative, and switch means for said non-self-starting electric motor which are closed by manual movement of said groove scanner arm.

4. A starting device for a non-self-starting phonograph comprising a non-self-starting electric motor, a turntable operatively connected thereto, a groove scanner arm mounted on a rod as a pivot to permit operative association with said turntable, a ratchet wheel fixedly

5 mounted on said rod, a plate segment mounted for pivotal movement and having gear teeth at the circumferential edge thereof, a pawl movably mounted on said plate segment and operatively associated with said ratchet wheel, a pivotal mounting, a pinion thereon, a wheel operatively associated with said pinion, said pivotal mounting movable to a first position wherein said pinion is in engagement with said gear teeth and said wheel is in engagement with said turntable and movable to a second position wherein said pinion is out of engagement with said gear teeth and said wheel is out of engagement with said turntable.

10 5. A starting device for a non-self-starting phonograph as in claim 4 wherein abutment means are provided on said plate segment for engaging said pivotal mounting whereby said pivotal mounting is moved to said first position in one position of said plate segment and to said second position in another position of said plate segment, stop means are provided which are operatively associated with said pawl mounted on said plate segment for moving said pawl into operative engagement with said ratchet in said another position of said plate segment and out of operative engagement with said ratchet in said one position of said plate segment, switch means for said non-self-starting motor are provided on said plate segment, said switch means being closed when said segment is in said another position, and spring means are provided for biasing said plate segment to said another position.
